CLAIM

The ornamental design for a home decorative light, as shown and described.

DESCRIPTION

FIG. 1 is a bottom perspective view of a home decorative light, showing my new design;

FIG. 2 is a top perspective view thereof;

FIG. 3 is a front view thereof;

FIG. 4 is a back view thereof;

FIG. 5 is a top view thereof; and,

FIG. 6 is a bottom view thereof.

In FIG. 5 and 6, the shorter dashed broken lines show portions of the article and do not form part of the claimed design. The longer dashed broken lines show a symbolic break that forms no part of the claimed design. The article is shown with a symbolic break in its length. The appearance of any portion of the article between the break lines forms no part of the claimed design.
